UNITED STATES PATENT OFFICE.

JAMES A. WIGGS, JR., OF BEAUMONT, TEXAS.

HYDRAULIC SWIVEL.

No. 810,315.

Specification of Letters Patent.

Patented Jan. 16, 1906.

Application filed April 3, 1905. Serial No. 253,563.

To all whom it may concern:

Be it known that I, JAMES A. WIGGS, Jr., a citizen of the United States, residing at Beaumont, in the county of Jefferson and State of Texas, have invented certain new and useful Improvements in Hydraulic Swivels; and I do hereby declare the following to be a full, clear, and exact description of the invention, such as will enable others skilled in the art to which it appertains to make and use the same.

This invention relates to hydraulic swivels for use in well-boring and similar work, and especially to that class or kind of such swivels which employs an inner water-tube or water-stem and a concentric tubular swivel-stem turning thereon and carrying the drill-stem attached to its lower end.

The chief objects of the said invention are to provide more perfectly for the exclusion of dust and foreign matter from the anti-friction-rollers and bearing-plates whereby the swivel-stem is carried on the trunnion-block; to improve the construction and arrangement of the devices connecting the swivel-stem rotatively to the water-stem and utilize the antifriction-balls thereof as interlocking means of suspension for the latter stem, not depending on friction alone for such service, and said balls being fitted closely by the proximate outer parts; to supply efficient spacing and bracing means between the trunnion-block and the drill-stem coupling, and generally to improve the details of the mechanism, all as hereinafter more particularly set forth and claimed.

In the accompanying drawings, Figure 1 represents a vertical central section of the mechanism embodying my invention. Fig. 2 represents a plan view of the grooved top of the upper stuffing-box G and the series of bearing-balls, I, which rest in the annular groove of said top. Fig. 3 represents perspective detail views of the two bearing-plates, slightly separated to show their inner construction. Fig. 4 represents a detail plan view of the upper bearing-plate. Fig. 5 represents a detail perspective view of the lower stuffing-box. Fig. 6 represents a vertical central section of a modification of the water-stem-supporting devices. Fig. 7 represents a detail perspective view of the grooved cap employed in the said modification; and Fig. 8 represents a view, similar to Fig. 6, of a further modification.

55 A designates the ordinary suspending-bail

of a hydraulic swivel; B, the usual trunnion-block, having trunnions b b held in the eyes of said bail by cap-plates c and screws c'; D, the tubular swivel-stem passing through the central bore of the trunnion-block and having its ends externally screw-threaded at d and d'; E, the water-stem or water-tube arranged concentrically within said swivel-stem and extending considerably above it, also provided at its upper end with external screw-threads e; F, the usual gooseneck, screwed on these latter threads and arranged to receive the water-supply; G, the upper stuffing-box, provided at its open lower end with internal screw-threads g, whereby it is screwed on upper threads d of the swivel-stem, and having at its upper end external screw-threads g' engaging internal threads h' of annular depending flange h of screw-cap H, centrally bored to fit the water-tube protruding upward through the same; I, the antifriction-balls arranged in circular series around this water-stem and between the said cap and stuffing-box; J, a lock-nut engaging threads d aforesaid and turning up against the said stuffing-box; K, the lower annular bearing plate or collar fast on the said trunnion-block and surrounding the swivel-stem; L, the corresponding upper bearing plate or collar, and M, the clamping-nut engaging the said threads d and holding the said upper plate in position.

As thus far described, the devices herein-after mentioned are not new; but I have invented the following improvements therein: The water-stem E is provided with an annular groove E', which receives and fits the antifriction-balls I. The cap H is provided with an internal annular groove H' at its lower edge, also exactly fitting the said balls at the upper and outer third or fourth part of their circumference, and the upper end of the stuffing-box G is provided with a similar groove G', which receives nearly all the remainder of each ball. When the cap H is screwed home, the said balls are held firmly in the groove E', preventing any looseness or rattling of the proximate parts and locking the said water-stem and the said swivel-stem at every point of their circumference against endwise movement, though permitting independent rotation of the said stuffing-box and the swivel-stem attached thereto, also the turning of the water-stem independently should such movement be desirable.

though the latter part normally remains fixed in the position shown. This function of the antifriction-balls and grooved water-stem is of course not dependent on friction, as in divers constructions heretofore in use rotatively connecting the water-stem to attachments of the swivel-stem, but absolutely prohibits any slip so long as the balls remain unbroken.

10 To permit lubrication of the ball-bearings, a shallow broad annular recess h^3 is left in the under face of cap H opposite the upper end of stuffing-box G and above the engaging screw-threads g^4 h^4 . A screw h^3 normally closes the oil-inlet hole h^4 , the latter having a screw-threaded annular wall and extending down through the said cap to the lubricating-space thus provided.

15 The stuffing-box G is much longer than those heretofore used for the same purpose. Its interior is filled with a number of packing-rings or washers N, alternating with metallic rings or equivalent partitions N', the whole constituting an efficient composite packing-pile which snugly fits both the interior of the said stuffing-box and the exterior of the said water-stem at all points, longitudinal as well as circumferential. The upper end of the swivel-stem is in contact with the 20 lower plate of this pile, and the turning of said stem or the said stuffing-box tightens the packing by compression, which the said plates transmit with approximate equality throughout the pile. Thus I am enabled to 25 apply a much greater mass of packing efficient in all its parts than would otherwise be feasible.

30 The bearing-plates K and L are not inclosed by any other part and incur no risk of peripheral friction therefrom. Plate K is provided outside of the antifriction-rollers with a raised annular flange k , fitting into an annular groove l' in the lower face of plate L, but not quite reaching the inverted bottom of said groove, to avoid needless friction. 35 The bearing-plate L is provided with a longer annular flange l , which overlaps the said flange k and nearly the whole peripheral face of plate L. These two flanges, with the inner wall of groove l' , exclude dust and foreign matter very effectively, but add practically nothing to the trouble or expense of casting the said plates, being very simple in form. Each of these bearing-plates, of course, is 40 provided with the usual groove having a transversely-inclined bottom k^2 or l^2 , fitting the conoidal antifriction-rollers O, arranged in circular series, the length of each roller corresponding to the width of the said 45 grooves. These rollers are large enough to hold the central portions of the said plates apart, leaving an annular space n for oil between the flange k and the water-stem. This space is supplied through a fine duct o 50 from an annular oil-groove O in the top of

bearing-plate L, said groove being normally covered by the nut M, and fed, while thus covered, through a duct m in said nut. The upper part of the wall of this latter duct is screw-threaded to receive a screw-plug m' , 55 closing the same at will.

60 The trunnion-block B is in contact with the upper end of a spacing and bracing sleeve P, screwed at its lower end on the lower threads d' of swivel-stem D, and at said end 75 contiguous to the screw-coupling Q, which connects the said swivel-stem to the drill-stem or drill-tube R. This connection is made by means of internal screw-threads q at the upper end of the said coupling, engaging 80 said threads d' of the swivel-stem, and external screw-threads q' at the lower end of the said coupling engaging internal screw-threads r of the upper end of the drill-stem. The 85 said parts being tightened by turning, the sleeve P is thereby clamped against the said trunnion and with the aid of the nut M holds the bearing-plates and their rollers securely in position. For lightness the interior of the 90 said sleeve is cut away around the swivel-stem nearly from end to end, as shown at p^2 . A blunt-headed screw S is turned through the said sleeve near its upper end against the 95 said swivel-stem and may be used when needed to take up wear, said screw not being turned tightly enough to impede the rotation of the swivel-stem and drill-stem in boring.

100 The lower end of the swivel-stem is provided with an internal recess T, surrounding the water-stem E, and the wall thereof is screw-threaded at t in the mouth of said recess. A gland U, fitting said water-stem and externally threaded, engages the threads t and when turned in compresses the packing 105 V of the said recess. The said gland is provided with peripheral projections W, permitting it to be turned by a wrench or equivalent tool inserted through the lower end of coupling Q.

110 The modification shown in Figs. 6 and 7 and the further modification shown in Fig. 8 make use of a collar X, internally screw-threaded at x and engaging screw-threads y on the upper part of the water-stem E, the 115 stuffing-box G and cap H, being provided with two opposite annular recesses Y and Y', together forming an annular chamber or raceway receiving said collar. This chamber is both wider from inner to outer face 120 and of greater measurement vertically than said collar to leave oil-space at the periphery of the latter and also under it. In the middle of the periphery of the said collar is an annular groove z , receiving the inner parts of the antifriction-balls I, the outer parts of 125 which above and below the center are received, as shown in Fig. 6, by grooves in the stuffing-box and cap G' H', arranged and constructed as in Fig. 1, but located farther out- 130

ward on account of the interposition of said cap.

The further modification illustrated in Fig. 8 has an exterior metallic band or collar X' concentric with collar X and similarly grooved in its inner face to receive the outer parts of antifriction-balls I, this outer band or collar being preferably composed of two annular sections divided on the horizontal plane of the centers of the said balls, as indicated by a division-line in Fig. 8.

The other elements shown in Figs. 6 and 8 are substantially identical with those hereinbefore described with reference to Fig. 1. The operation of the parts is also substantially the same.

The boring is, as usual, carried on under heavy hydraulic pressure, water being forced down the water-stem E to carry off the material cut away, as well as to aid in the cutting. Of course the back pressure is often very great. Hence the need of holding said stem down to its position by interlocking engagement of parts, as in Figs. 1 and 6, and not trusting to frictional contact only.

The modifications shown in Fig. 6 effect this result, as well as the construction shown in Fig. 1, since the collar X while in use is practically integral with the water-stem E, though of course separable therefrom by proper turning, and cannot be stripped off except by very great back pressure. Said modifications have the advantage of facilitating repairs, especially when the parts proximate to the antifriction-balls I have become worn. The grooving of the water-stem itself, as illustrated in Fig. 1, requires this part to be made of heavy hydraulic pipe, for which a substitute cannot be readily found when in use at a great distance from the factory. Transferring the groove to a separable collar permits a lighter pipe, with correspondingly lighter stuffing-box and cap, to be used. In many instances the substitution of a new collar X, with unworn groove, will suffice, and there will very seldom be any need to remove the water-stem itself. Also the decreased massiveness of all the parts will make it much more feasible to execute repairs on the spot or to keep extra caps and stuffing-boxes on hand for substitution as needed.

In all three of these constructions the introduction of the packing from below into stuffing-box G makes any additional follower unnecessary, as the upper end of the swivel-stem performs this function. The said stuffing-box answers the double function of holding the said packing on the water-stem and of forming a part of the devices rotatively connecting said swivel-stem and water-stem and suspending the latter locked against vertical movement. The packing of the swivel-stem at both ends is necessary, because the water, being under great pressure, would other-

wise force fragments of stone and other material in between the said stems, preventing the rotation of the swivel-stem.

The general operation is simply that of all such mechanism and has been hereinbefore sufficiently indicated or described.

Having thus described my invention, what I claim as new, and desire to secure by Letters Patent, is—

1. In a hydraulic swivel, a tubular, suspended water-stem, having an annular groove in its exterior near its upper end, in combination with a swivel-stem surrounding the same, means for suspending the said swivel-stem, a series of antifriction-balls fitting in the groove of said water-stem to suspend the same and prevent its endwise displacement, a stuffing-box attached to said swivel-stem and grooved at the top to fit the said balls, and a cap screwing down on the said stuffing-box and also grooved to fit the said balls, the grooves in said cap and stuffing-box permitting the said swivel-stem to turn independently on the said water-stem substantially as set forth. 90

2. In a hydraulic swivel the combination of a water-stem having an annular groove E' with a swivel-stem concentrically arranged thereon, a part screwed on the upper end of of the said swivel-stem and having an annular groove G' in its top in proximity to groove E' and a cap H screwed on said part thus grooved in its top, recessed on its under side above the screw-threads to provide an oil-space, having a duct and plug for the supply thereof and further provided with a groove H' in proximity to the grooves before mentioned, means for supporting the said swivel-stem and a series of antifriction-balls, fitting in the three grooves aforesaid to connect the said water-stem to the said swivel-stem and permit swiveling motion but suspend the said water-stem from the said swivel-stem and prevent vertical displacement substantially as set forth. 100

3. In a hydraulic swivel, the combination of a water-stem and swivel-stem, concentrically arranged, with a bail and trunnion for suspending the said swivel-stem, a bearing-plate mounted on said trunnion and having on its surface an annular groove and an annular raised flange, antifriction-rollers located in said groove, an upper bearing-plate provided with a groove for said antifriction devices, another groove to receive said flange and a downwardly-extending flange outside of the latter and of the body of said lower bearing-plate, and means carried by the said swivel-stem for holding the said upper bearing-plate in position, the said flanges and the walls of the groove in the upper bearing-plate which receives the flange of the lower bearing-plate serving as dust-guards for the said antifriction devices substantially as set forth. 110 115 120 125 130

4. In a hydraulic swivel, the combination of a water-stem and a swivel-stem, concentrically arranged, with means for supporting said water-stem from said swivel-stem and means for suspending said swivel-stem, the latter means including a pair of bearing-plates and interposed antifriction devices and the said plates being provided with overlapping flanges, independent of any other part of the machine, for excluding dust and other foreign matter from said antifriction devices substantially as set forth.
5. In a hydraulic swivel the combination of a water-stem and a swivel-stem, concentrically arranged, of means for supporting said water-stem by said swivel-stem, a ball and trunnion-block for suspending the said swivel-stem, a bearing-plate fixed on said trunnion, an upper bearing-plate turning on the same and having an oil-trough in its upper face, whence a duct extends down to its lower face, a nut threaded on said swivel-stem provided with an oil-supply duct for said trough and bearing against said upper bearing-plate to hold it in position and a series of antifriction devices interposed between the said two bearing-plates, the latter being constructed to leave an oil-space between them about the said antifriction devices and provided with means for excluding dust and

other foreign material from the latter substantially as set forth.

6. In a hydraulic swivel, the combination of a water-stem and a swivel-stem, concentrically arranged, with means connecting the stems but allowing the swiveling action, a bail and trunnion-block provided with antifriction devices and bearing-plates, for suspending the said swivel-stem, and a spacing-sleeve screwed on the said swivel-stem for contact with the lower side of the said trunnion substantially as set forth.

7. In a hydraulic swivel, the combination of a water-stem and a swivel-stem, concentrically arranged, of means for connecting said stems together but allowing swiveling action, a block sleeved on said swivel-stem and provided with means for suspending the latter, a sleeve in contact with the under side of said block, a screw-threaded coupling arranged to hold said sleeve against said block and a depending tubular stem connected to said coupling substantially as set forth.

In testimony whereof I have signed my name to this specification in the presence of two subscribing witnesses.

JAMES A. WIGGS, JR.
